(57) **CLAIM**

The ornamental design for the cooler for beverage containers, as shown and described.

DESCRIPTION

FIG. 1 is a front perspective view of a cooler for beverage containers incorporating my new design;
FIG. 2 is a bottom perspective view thereof;
FIG. 3 is a top plan view thereof;
FIG. 4 is a bottom plan view thereof;
FIG. 5 is a right or left side view thereof;
FIG. 6 is a front elevation view thereof; and,
FIG. 7 is a top perspective view thereof.

The broken lines shown in the drawings illustrate portions of the cooler for beverage containers that forms no part of the claimed design.
